GLIDING SWING ROCKER

Filed Sept. 29, 1933

UNITED STATES PATENT OFFICE

1,986,233

GLIDING SWING ROCKER

Earl L. Weaver, Goshen, Ind., assignor to The
Goshen Manufacturing Company, Goshen, Ind.

Application September 29, 1933, Serial No. 691,527

5 Claims. (Cl. 155—57)

This invention relates to improvements in gliding swing rockers of the general type shown in United States Letters Patent to Boyer, No. 1,176,271 of March 21, 1916, for Swings.

5 The objects of this invention are:

First, to provide an improved construction of double rocker for such a swing.

Second, to provide a glider swing rocker formed entirely of a sheet metal stamping and 10 one which is well adapted to withstand twisting and bending forces, and is attractive in appearance.

Third, to provide a rocker assembly with the parts arranged and adapted so that the rocker 15 assembly may be dismantled from the swing without disassembling the rocker assembly.

Fourth, to provide an improved rocker lug and movement limiting link assembly.

Fifth, to provide a rocker assembly for swings 20 having the above desirable features and characteristics, which is simple and economical in its parts and quiet and efficient in operation.

Objects relating to details and economies of 25 my invention will appear from the description to follow. The invention is defined and pointed out in the claims.

A structure which is a preferred embodiment of my invention is illustrated in the accompanying drawing, in which:

30 Fig. 1 is a view in side elevation of a swing embodying the features of my invention.

Fig. 2 is an enlarged fragmentary vertical section on a line corresponding to line 2—2 of Fig. 3.

35 Fig. 3 is a perspective view of the rocker assembly removed from the swing.

Fig. 4 is an enlarged fragmentary detail section on a line corresponding to line 4—4 of Fig. 3.

40 Fig. 5 is a fragmentary view in side elevation showing the connection between the link and lug.

Referring to the embodiment of my invention 45 illustrated in the drawing, the platform or base 1 is provided with suitable ways 2 which are arranged in spaced substantially parallel relation. A pair of chairs or seats 3 are disposed above the platform and are connected by frame bars 4. The chairs include pairs of legs or uprights 5 and 6, the parts being rigidly secured together by suitable means. Diagonal braces 7 couple these uprights and bars together and serve to provide supports for the backs of the chairs or seats.

55 Side bars 8 are beneath the seat bottoms and

are provided with suitable ways for receiving the rockers. Curved bars 9 connect the lower ends of the standards or legs 5 together and engage under suitable guide lugs 10 on the side of the frame bars of the platform.

Each of the chairs is provided with a roller or rocker assembly consisting of a pair of spaced parallel rollers or rockers 11 and a pair of upper and lower cross connecting rods 12 connecting the rockers in assembled relation. Each rocker 10 is formed of sheet metal and is provided with upper and lower curved rocker bearing surfaces 13 and inwardly extending and outwardly facing opposed side recesses 14. An inturned peripheral flange 15 extends continuously around the bearing surfaces and in the side recesses and acts to stiffen and reinforce the structure and to provide suitable width for the bearing surfaces 13.

The web 45 of the rocker is provided with upper and lower connecting rods holes 16 and 20 upper and lower lug openings 17 disposed on one side of the connecting rod holes. Annular web stiffening beads 18 and 19, respectively, surround the holes 16 and openings 17. Similarly formed vertical ribs 20 are disposed in the web 25 above and below the holes 16 and inwardly curved substantially vertical ribs 21 are disposed in the web between the holes 16 and the side recesses 14. The ribs are pressed outwardly and coact with the inwardly extending peripheral flange 15 to strengthen and reinforce the web 30 against twisting and bending forces.

The ends of the connecting rods 12 extend through the holes 16 and are provided with end nuts 22 on the outside of the web and with 35 cupped heads 23 on the inside of the web, the head engaging projections 24 struck up from the rod, as illustrated by Fig. 2. With the parts thus arranged, the two connecting rods 12 rigidly secure the rockers in assembled relation. 40 The structure is formed entirely of metal and creaking and other objectionable noises are thereby entirely eliminated.

Movement limiting or stop links 25 and 26 are 45 pivotally connected to the chair side bars at 27 and to the side rails of the platform at 28, respectively. Each link is provided with a longitudinal slot 29 at its outer end for coaction with the annular groove 30 at the inner end of the lug 31 which is riveted to the web in the 50 opening 17 as illustrated by Figs. 4 and 5. The lug is provided with upper and lower lands 32 which extend from the groove to the outer end of the lug. The sides 33 of the end of the lug 55 are spaced apart a distance substantially equal

to the diameter of the base of the groove. With the parts thus arranged, the link is readily assembled with and detachable from the lug by swinging it so that the slot is in registry with the lands. Thus each rocker assembly unit may be removed from the swing without disassembling the rocker unit. The links in operation limit the movement and insure alinement of the rockers.

10 In my improved construction, all rivets and wooden parts which would tend to draw or stretch the rockers out of shape and all joints which might work loose and squeak are entirely eliminated. The beading pressed in the rocker 15 strengthens and stiffens the rocker web. All corners are rounded and projections or sharp edges are eliminated, thereby offering protection against personal injury. Only two connecting rods with their attaching heads and end nuts are used in each rocker assembly. This makes 20 the structure very simple and easy to assemble and one which is strong, yet comparatively inexpensive. Further, the settee can be taken apart for storage without separating the rockers.

25 I have illustrated and described my improvements in an embodiment which I have found very practical. I have not attempted to illustrate or describe other embodiments or adaptations, as it is believed this disclosure will enable those skilled in the art to embody or adapt my improvements as may be desired.

Having thus described my invention, what I claim as new and desire to secure by Letters Patent, is:

35 1. A rocker assembly for swings of the class described, comprising in combination a pair of spaced parallel sheet metal rockers each formed of an integral sheet of metal and having opposed side recesses, a continuous inturned peripheral flange, a pair of aligned connecting rod holes and pressed web stiffening beads surrounding said holes and vertical pressed web stiffening ribs disposed above and below and at the sides of said holes, and a pair of metal cross connecting rods bolted to said rockers in said holes and connecting the parts in assembled relation.

2. A rocker for swings of the class described, comprising a sheet metal web having a continuous inturned peripheral flange and upper and lower curved peripheral bearing surfaces, outwardly facing opposed side recesses, upper and lower connecting rod holes, upper and lower lug

openings at one side of said holes, annular web stiffening beads surrounding each of said holes and openings in substantial spaced relation, vertical web stiffening ribs above and below said holes and inwardly curved web stiffening ribs disposed between said holes and said recesses, said beads being pressed outwardly and acting with the inwardly extending peripheral flange to strengthen and reinforce the web against twisting and bending forces.

3. A rocker for swings of the class described, comprising a sheet metal web formed of an integral sheet of metal and having upper and lower curved bearing surfaces, an inwardly extending continuous peripheral flange, vertically aligned connecting rod holes, lug openings, annular web stiffening beads surrounding each of said holes and openings in substantial spaced relation, vertical web stiffening ribs above and below said holes and inwardly curved web stiffening ribs disposed at opposite sides of said holes, said ribs being pressed outwardly and acting with the inwardly extending peripheral flange to strengthen and reinforce the web against twisting and bending forces.

4. A rocker for swings of the class described, comprising a web having upper and lower curved bearing surfaces, outwardly facing opposed side recesses, an inwardly extending peripheral flange on its curved bearing surfaces, vertically aligned connecting rod holes, lug openings, annular web stiffening beads surrounding each of said holes and openings, and vertical web stiffening ribs above and below and at the sides of said holes, said ribs being pressed outwardly and acting with the inwardly extending peripheral flange to strengthen and reinforce the web against twisting and bending forces. 25 35

5. In a swing structure having a rocker, the combination of a lug secured to the rocker and having an annular groove and side lands extending from the groove to the projecting end of the lug, and a detachably pivoted movement limiting link having a longitudinal slot coacting with said groove, the width of said slot being slightly larger than the width of the lug between said lands whereby the link may be slipped on and off of the lug by bringing the slot and lands into registry, the normal position of the parts being such that the slot and lands are not in registry. 50
